UNITED STATES PATENT OFFICE

2,494,434

CONDENSATION DRAIN VALVE

Clyde C. Farmer, Pittsburgh, Pa., assignor to The Westinghouse Air Brake Company, Wilmerding, Pa., a corporation of Pennsylvania

Application November 16, 1943, Serial No. 510,472

10 Claims. (Cl. 230—1)

1

This case relates to steam driven compressor equipments, and particularly to a condensation drain valve device operative to discharge water condensed in the steam supply pipe and steam cylinders of such a compressor.

In certain railroad properties, particularly those situated in northern or mountain territories, where trains must be operated under freezing weather conditions, the condensation of moisture in the steam pipe and steam cylinders of the compressor carried on each locomotive has in the past inspired the development of various means for draining such moisture from the system. The drain valve devices heretofore proposed have not demonstrated the necessary degree of reliability, however, either because of poor design and construction, or by reason of a general unfitness for association with a steam driven compressor operated under the severe conditions encountered in railroad service.

It is the principal object of my invention to provide an improved automatic means for draining any moisture or condensate from the steam pipe, steam cylinders, or the other parts of a steam driven air compressor equipment.

Other objects and advantages of the invention will appear in the following more detailed description, thereof, taken in connection with the accompanying drawing, in which

Fig. 1 is a schematic view of a steam driven compressor equipment for a locomotive, having associated therewith a condensation drain valve device constructed in accordance with one form of my invention;

Fig. 2 is an enlarged detail view, partly in section, of the governor device forming part of the equipment shown in Fig. 1; and

Fig. 3 is a sectional view of a condensation drain valve device embodying another form of the invention.

The apparatus shown in Fig. 1 includes a steam driven compressor 5 which is operative to supply compressed air to a main reservoir 6 through a suitable pipe (not shown), a compressor governor device 7 for controlling the supply of steam to the compressor, and a condensation drain valve device 8. The compressor governor device 7 is constructed and arranged to control the supply of steam by way of a steam pipe 10 to the steam cylinders 5a and 5b of the compressor 5, in accordance with the pressure maintained in the main reservoir 6, which is connected with the fluid pressure responsive portion of the governor device through the medium of a pipe 11.

The compressor governor 7 may be of any

suitable design, and as disclosed in Fig. 2 may comprise a casing 14 interposed in the steam supply pipe 10 and containing a suitable steam valve (not shown), which is operated by a piston 15 to cut off the flow of steam through the pipe 10. The piston 15 is subject to the pressure of air that can be supplied to a normally vented chamber 17 by operation of a valve element 18, contained in a valve chamber 19 that communicates with the pipe 11 leading to the main reservoir. The valve element 18 is adapted to be actuated by a diaphragm 21 which is interposed between the valve chamber 19 and a coil spring 22 carried in a compressor top 23. It will be understood that so long as the pressure in the main reservoir, pipe 11 and valve chamber 19 of the governor device remains below a predetermined maximum value, the spring 22 will maintain the valve 19 on its seat, while the piston 15 will be held in its uppermost position, as shown in Fig. 2, to permit flow of steam through the pipe 10 to the compressor. When the pressure of air in the main reservoir exceeds the predetermined maximum value, however, the corresponding pressure acting on the diaphragm 21 becomes effective to lift the diaphragm upwardly, thereby permitting unseating of the valve element 18 by a spring 24 associated therewith, so that compressed air can be supplied to the piston chamber 17 for operating the piston 15 to close the steam valve.

According to the invention, the condensation drain valve device 8 comprises a casing structure 26 having formed therein a condensate drainage chamber 28, which communicates with a drainage opening 29 and with a pair of valve bores 30 and 31. The valve bore 30 is connected by way of a branch pipe 32 to the steam supply pipe 10, and has slidably mounted therein the fluted stem of a discharge valve element 33, which is adapted to engage a seat 34 for controlling the admission of condensate from the pipe 32 and bore 30 to the drainage chamber 28. The other valve bore 31, communicates by way of a branching pipe 37 with the respective steam cylinders 5a and 5b of the steam driven air compressor 5. Mounted in the valve bore 31 is the fluted stem of a discharge valve element 39, which is engageable with a seat 40 for controlling communication from the bore 31 to the drainage chamber 28.

Clamped in the casing structure 26 beneath the two discharge valve elements 33 and 39 is a flexible diaphragm 43, which is interposed between the drainage chamber 28 and a pressure chamber 44 communicating by way of a restricted passage 46, a pipe 45, and the pipe 11 with the main reser-

voir 6. A follower member 47 carried by the flexible diaphragm 43 is disposed in rocking engagement with a tiltable beam 48, which is in turn adapted to engage the two discharge valve elements 39 and 33. Interposed between an upper wall of the chamber 28 and the end of the beam 48 adjacent discharge valve element 39 is a coil spring 52. Similarly, a coil spring 53, preferably of less power than the spring 52, is interposed between the casing structure and the other end of the beam 48 adjacent the discharge valve element 33. It should be understood, however, that the pressure of air normally present in the diaphragm chamber 44, which communicates by way of the restricted passage 46 and pipe 45 with the main reservoir as already explained, is effective through the medium of the diaphragm 43, follower member 47 and beam 48 to hold the valve elements 39 and 33 in their seated positions, as shown in Fig. 1.

The casing structure 26 further includes a pilot valve portion 26a, within which is mounted a flexible diaphragm 55, that is subject on its lower side to the pressure of air in a diaphragm chamber 56 communicating by way of a pipe 57 with the piston chamber 17 of the compressor governor device 7, as may be seen by reference to Fig. 2. At the upper side of the diaphragm 55, in the casing portion 26a, is formed a chamber 59 communicating with the atmosphere by way of a port 60, and also connected past a valve seat 61 with a valve chamber 62, which in turn communicates by way of a port 63 with the diaphragm chamber 44. Mounted in the valve chamber 62 is a valve element 65, which is normally held in seated position by the force exerted by a coil spring 66, and which has a fluted stem 67 disposed in engagement with the diaphragm 55. The diaphragm 55 is thus arranged to unseat the valve element 65 upon an increase in the pressure of fluid in the chamber 56.

In operation, the two discharge valve elements 39 and 33 are normally held in their seated positions, as shown, by the pressure of air supplied to the diaphragm chamber 44 from the main reservoir 6, while the valve element 65 is held on the seat 61 by the spring 66 so long as the diaphragm chamber 56 is connected to atmosphere through the pipe 57, the chamber 17 of the governor device 7 as shown in Fig. 2, and a suitable atmospheric port provided in that device but not shown in the drawing. Moisture condensed from the steam in the supply pipe 10 is free to flow therefrom through pipe 32 to the valve bore 30 in the drain valve device 8, and at the same time moisture accumulating in the steam piston chambers 5a and 5b of the compressor 5 is conducted therefrom through the pipe 37 to the other valve bore, 31, in the drain valve device.

It will be understood that operation of the governor device 7 to control the flow of steam through the pipe 10 is dependent upon variations in the pressure of air in the main reservoir 6, and may consequently not be repeated at regular intervals, but under usual service conditions it is to be expected that the governor device will operate frequently enough to cause the drain valve device 8 to function to expel condensate in chamber 28 in an efficient manner. Upon each increase in main reservoir pressure to the maximum value for which the governor device 7 is set, the valve element 18 thereof is unseated to supply compressed air from the pipe 11 to the piston chamber 17, thereby actuating the piston 15 to close the steam valve controlling flow of steam through the pipe 10 to the compressor.

Air under pressure is at the same time supplied from the piston chamber 17 through the pipe 57 to the diaphragm chamber 56 of the drain valve device 8 for moving upwardly the diaphragm 55 and valve element 65. When the valve element 65 is unseated, air under pressure is discharged from the diaphragm chamber 44 by way of the passage 63, valve chamber 62, diaphragm chamber 59 and port 60 at a rate faster than that at which air can be supplied to the diaphragm chamber 44 by way of the restricted passage 46, so that the pressure acting on the diaphragm 43 is substantially reduced.

When this occurs, the springs 52 and 53 are rendered effective to move the beam 48, follower member 47 and the diaphragm 53 downwardly for permitting the discharge valve elements 39 and 33 to assume their respective unseated positions. Since the spring 52 is stronger than the spring 53, the beam 48 will normally be somewhat tilted during this operation to permit unseating of the valve element 39 before the valve element 33 is unseated, thereby allowing time for the steam pressure in the supply pipe to drive all condensate from the compressor cylinders to the drain valve device. Accumulated condensate is then drained from the respective bores 31 and 30 into the chamber 28, from which the condensate is discharged by way of the port 29.

When the pressure of air in the main reservoir subsequently drops below the predetermined minimum value for which the governor device 7 is set, the spring 22 of the governor device, shown in Fig. 2, again moves the valve element 18 to its seated position, thus cutting off further supply of air to the piston chamber 17, which is meanwhile vented to the atmosphere through the usual discharge port, not shown. At the same time compressed air is vented through the same communications from the diaphragm chamber 55 of the drain valve device 8, until the spring 66 once more becomes effective to seat the valve element 65. With the valve element 65 in seated position, main reservoir air again accumulates in the diaphragm chamber 44 by flow through the pipe 45 and restricted passage 46. The increasing pressure of air finally forces upwardly the diaphragm 43, follower member 47 and beam 48 to seat, in sequence, the discharge valve element 33 and the discharge valve element 39. The valve element 39 is thus held open long enough to insure discharge of the condensate supplied through both branches of pipe 31. The drainage communications from the steam supply pipe 10 and the steam cylinders of the compressor 5 are thus again closed, pending a further operation of the governor device 7, as hereinbefore explained.

Referring to Fig. 3 of the drawing, the condensation drain valve device therein disclosed is designed for operation on the same principle as that in the case of the device 8 shown in Fig. 1, although the structural features embodying the invention are of a different form. The condensation drain valve device shown in Fig. 3 comprises a casing structure 70 having mounted therein a flexible diaphragm 71, which is interposed between a pressure chamber 72 connected by way of the pipe 45 with the main reservoir, and a drainage chamber 73 communicating with a discharge or drainage port 74. Formed in the casing structure 70 is a valve bore 76, connected to the pipe 32 leading to the steam supply pipe, and a valve bore 77, which is connected to the pipe 37 leading from the steam cylinders of the

compressor. A discharge valve element 80 is provided for controlling communication from the valve bore 76 to the chamber 73, and a similar discharge valve element 81 is mounted in the casing structure for controlling communication from the other valve bore 77 to the chamber 73, both valves being normally held in their respective seated positions by the pressure of air in the diaphragm chamber 72 acting through the medium of the diaphragm 71, a follower element 85, and a beam 86 rockably mounted on the follower element.

It will be noted that the beam 86 is mounted eccentrically with respect to the follower member 85, and is subject to the force exerted by a coil spring 90 which urges the beam downwardly, or in opposition to the air pressure acting on the diaphragm 71. The coil spring 90 engages the beam 86 somewhat to one side of the point at which that member is fulcrumed on the follower member 85, so that the force of the spring is distributed unequally to the respective valve elements 81 and 80. With the greater portion of the force exerted by the spring 90 transmitted to the end of the beam 86 engaging the valve element 81, the valve element 80 is thus adapted to remain in seated position longer than the other valve element 81 upon downward movement of the assemblage, and likewise to assume its seated position prior to the seating of the valve element 81 when the associated elements are moved upwardly, as viewed in the drawing.

In operation, air at the pressure maintained in the main reservoir is supplied through the pipe 57 to the diaphragm chamber 72 for normally maintaining the diaphragm 71, follower element 85, beam 86 and discharge valve elements 81 and 80 in the positions in which they are illustrated in Fig. 3. At such time water condensed from the steam being supplied to the associated compressor is supplied through the pipe 32 to the valve bore 76, and through the pipe 37 to the other valve bore 77. When the pressure of air in the main reservoir falls below a predetermined value as determined by the force exerted by the coil spring 90 in the condensation drain valve device, the spring is enabled to force downwardly the beam 86, follower member 85 and diaphragm 71 for unseating, in sequence, first the discharge valve element 81 and then the discharge valve element 80. When the discharge valve elements are unseated, condensed moisture is free to flow out by way of the chamber 73 and drainage port 74. A subsequent increase in main reservoir pressure, and in the corresponding pressure of air in the diaphragm chamber 72, is effective to return the various elements to the position shown in Fig. 3 for cutting off further drainage of condensate. It will be apparent that the device shown in Fig. 3 is designed for association with a compressor equipment operative to restore main reservoir pressure to the predetermined maximum value in a short time following a temporary reduction, such as that just described, so that the discharge valve elements 81 and 80 will be unseated for short intervals only.

From the foregoing description it will be seen that a condensation drain valve device constructed in accordance with my invention may readily be installed in an existing steam driven compressor equipment for automatically reducing the accumulation of condensate to a minimum. The automatic operation of the drain valve device is achieved without the addition of

expensive operating devices to the apparatus, and may be embodied in a simple, sturdy structural unit adapted to withstand the severe operating conditions encountered in railway service.

Having now described my invention, what I claim as new and desire to secure by Letters Patent is:

1. A drain valve device comprising a casing structure having a plurality of portions for accumulating condensate, a condensate drainage chamber and a pressure chamber, a movable abutment interposed between said chambers, a plurality of discharge valve elements controlled by said abutment for individually controlling flow of condensate from said portions to said condensate drainage chamber, and spring means constructed and arranged to act on said abutment in opposition to the pressure of fluid in said pressure chamber for effecting sequential operation of said valve elements.

2. A liquid drain valve device comprising a casing having a plurality of portions for accumulating liquid, a liquid drainage chamber and a pressure chamber, an individual discharge valve element for each portion for controlling the flow of accumulated liquid therefrom to said liquid drainage chamber, movable abutment means interposed between said chambers and responsive to variations in the pressure in said pressure chamber for actuating said discharge valve elements, fluid pressure operated valve means for controlling the pressure in said pressure chamber, and spring means exerting unequally divided pressure on said diaphragm in opposition to the pressure in said pressure chamber for effecting sequential operation of said valve elements.

3. The combination with a steam driven air compressor system, a steam driven air compressor, a steam pipe for supplying steam to said compressor, and a reservoir for receiving air supplied by the compressor, of a governor device responsive to variations in the pressure of air in said reservoir for controlling the flow of steam through said steam pipe, a drain valve device comprising a casing having a condensate discharge chamber and a pressure chamber, a discharge valve element controlling communication between said compressor and said discharge chamber, a discharge valve element controlling communication between said steam pipe and said discharge chamber, movable abutment means responsive to variations in the pressure of air in said pressure chamber for actuating said abutment means, valve means controlled in accordance with the operation of said governor device for varying the pressure of air acting on said movable abutment means, and spring means exerting a pressure on said diaphragm in opposition to the pressure of air in said pressure chamber, said spring means being unbalanced with respect to the valve elements to effect the operation of the first named valve element before the second named valve element.

4. The combination with a steam driven air compressor system comprising a steam driven compressor having a steam pipe for supplying steam to the compressor, and a reservoir for receiving fluid under pressure supplied by the compressor, of a governor device responsive to variations in the pressure of fluid in said reservoir for controlling the flow of steam through said steam pipe, and a drain valve device com-

prising a casing having a chamber in open communication with said reservoir and therefore charged with fluid under pressure therefrom, and valve means comprising a valve operative to an open position upon a reduction in the pressure of fluid in said chamber to effect discharge of condensate from a plurality of selected points in said compressor system and operative to a closed position upon a subsequent increase in the pressure of fluid in said chamber, and valve means responsive to operation of said governor device for controlling the pressure of fluid in said chamber.

5. The combination with a steam driven compressor system comprising a steam driven compressor, and a reservoir charged with fluid under pressure supplied by said compressor, of a compressor governor device responsive to variations in pressure of fluid in said reservoir for controlling the supply of steam to said compressor, a condensation drain valve device comprising a casing having a plurality of chambers for receiving condensate accumulating at selected points in said compressor system, a plurality of discharge valve elements in said drain valve device operative to discharge condensate from said chambers, movable abutment means subject to the pressure of fluid in said reservoir and operable for actuating said discharge valve elements upon a reduction in the pressure of fluid acting on said abutment, and other valve means controlled in accordance with the operation of said governor device for varying the pressure of fluid acting on said movable abutment means, whereby said drain valve device is rendered operative to discharge condensate in response to operation of said governor device.

6. The combination with a steam driven compressor system comprising a steam driven compressor, and a reservoir charged with fluid under pressure supplied by said compressor, a compressor governor device, of a condensation drain valve apparatus comprising a casing having a pressure chamber and having discharge valve means operative to discharge condensate accumulating in said compressor system, movable abutment means subject to the pressure of fluid in said pressure chamber, a restricted communication for supplying fluid at a restricted rate from said reservoir to said pressure chamber, valve means operative to discharge fluid under pressure from said pressure chamber at a rate faster than that of the supply through said restricted communication, and a movable abutment subject to variations in the pressure of fluid in said governor device for controlling said valve means.

7. A liquid drain valve device comprising a casing having a plurality of portions for accumulating liquid, a liquid drainage chamber and a pressure chamber, an individual discharge valve element for each portion for controlling the flow of liquid therefrom to said liquid drainage chamber, movable abutment means interposed between said chambers and responsive to variations in pressure in said pressure chamber for actuating the discharge valve elements, means for varying the pressure of fluid in said pressure chamber, and pressure means exerting an unequally divided pressure on said movable abutment means in opposition to the pressure in said pressure chamber for effecting sequential operation of said valve elements.

8. A drain valve device comprising a casing 75

structure having a plurality of liquid collecting portions supplied with fluid under pressure from a common source, a liquid drainage chamber and a pressure chamber, an individual discharge valve element mounted in each portion and subject respectively to the fluid pressure in one of said portions, each of said elements having a closed position and both being actuatable in the same direction for establishing communication between 10 said portions and said drainage chamber, fluid pressure responsive means comprising a movable abutment interposed between said pressure chamber and said liquid drainage chamber, lever means rockably mounted on said fluid pressure 15 responsive means operable thereby to actuate said elements to their closed positions, said lever means comprising a plurality of arms, one for each valve element, and engaging said valve elements at points equi-distant from the point of 20 said rockable mounting, and an individual spring operably engaging each of said arms at points equi-distant from the point of said rockable mounting, the springs exerting different pressures in opposition to the pressure in said pressure chamber for effecting sequential operation of 25 said valve elements.

9. A drain valve device comprising a casing structure having a plurality of liquid collecting portions supplied with fluid under pressure from 30 a common source, a liquid drainage chamber and a pressure chamber, an individual discharge valve element mounted in each portion and subject to the fluid pressure in the respective portion, each of said elements having a closed position and all 35 being actuatable in the same direction for establishing communication between said portions and said drainage chamber, fluid pressure responsive means comprising a movable abutment interposed between said pressure chamber and said 40 drainage chamber, and lever means rockably mounted on said fluid pressure responsive means for actuating said elements to their closed positions, said lever means comprising a plurality of arms, one for each valve element, and engaging 45 said valve elements at various distances from said rockable mounting for effecting sequential operation of said valve elements.

10. The combination with a steam driven compressor system comprising a steam driven compressor, a reservoir charged with fluid under pressure supplied by said compressor, and a compressor governor device, of a condensation drain valve device comprising a casing structure having a plurality of liquid collecting portions supplied with fluid under pressure from said system, a liquid drainage chamber and a pressure chamber, an individual discharge valve element mounted in each portion and subject to the fluid pressure in the respective portion, each of said 55 elements having a closed position and all being actuatable in the same direction for establishing communication between said portions and said drainage chamber, fluid pressure responsive means comprising a movable abutment interposed between said pressure chamber and said drainage chamber, and lever means rockably mounted on said fluid pressure responsive means for actuating said elements to their closed positions, said lever means comprising a plurality of arms, one for each valve element, and engaging 60 said elements at various distances from said rockable mounting for effecting sequential operation of said valve elements.

Certificate of Correction

January 10, 1950

Patent No. 2,494,434

CLYDE C. FARMER

It is hereby certified that errors appear in the printed specification of the above numbered patent requiring correction as follows:

Column 6, line 17, after the word "said" insert *movable*; line 35, for "diaphragm" read *movable abutment means*; column 8, line 2, after "portions" insert the comma and words, *each being*; line 3, for "a common source" read *its source of liquid supply*; and that the said Letters Patent should be read with these corrections therein that the same may conform to the record of the case in the Patent Office.

Signed and sealed this 6th day of June, A. D. 1950.
